UNITED STATES PATENT OFFICE.

EZRA ARTHUR NEWHALL, OF PORTLAND, MAINE.

ALARM-BELL.

SPECIFICATION forming part of Letters Patent No. 656,851, dated August 28, 1900.

Application filed April 16, 1900. Serial No. 13,048. (No model.)

To all whom it may concern:

Be it known that I, EZRA ARTHUR NEWHALL, a citizen of the United States, residing at Portland, in the county of Cumberland and State of Maine, have invented certain new and useful Improvements in Alarm-Bells; and I do hereby declare the following to be a full, clear, and exact description of the invention, such as will enable others skilled in the art to which it appertains to make and use the same.

The invention relates to alarm-bells intended for use on bicycles and the like; and the object in view is to provide a bell of this description which is simple in construction and which may be rung continuously for some time by a single impulse.

The invention is illustrated in the accompanying drawings, wherein—
20 Figure 1 is a vertical central section. Fig. 2 is a plan view of the same with the crown of the bell removed, showing the cup portion and the interior works; and Fig. 3 is a side view of the cup and the bracket for securing the bell to the machine.

Referring to the views, 1 denotes a bracket composed of clamping-plates 2 2, shaped to fit the handle-bar or other part of the machine to which the bell is to be attached. The 30 plates 2 2 are clamped together by threaded bolts 3 3, and one end of the top plate is preferably provided with an extension 4 for a purpose which will be described later on.

Rigidly secured to the top plate of the 35 bracket and projecting vertically from the center thereof is a post d, and at the upper end of the post the crown e of the bell is secured in any suitable manner. Below the crown e there is sleeved upon the post, so as 40 to turn freely, a cup b of any convenient shape and having its upper edge fitting within the depending edge of the crown e. In the upper part of this cup there is secured a disk a, the attachment between the cup and the disk being formed by notching the disk at suitable points around its periphery, as at a', and locking the disk to the cup by strips b', the lower ends of which are fastened to the cup and whose upper ends fit into the notches and are 45 clenched over the edge of the disk, thus securely fastening the disk and the cup together,

so that they may be revolved together around the post d.

Rising from the plate a are pins or elongated rivets p, and secured to the upper ends of these pins is another plate a², similar to the plate a. The plate a² is also sleeved upon the post d and being rigidly connected by the pins p with the plate a moves with it. Between these two plates a and a² are mounted 60 the train of gears c c c' c² for ringing the bell, the clapper i, and the star-wheel j, as will now be described.

The post d is preferably shouldered at a point about midway of its length, and a 65 ratchet-wheel f, with teeth pointing in one direction only, is secured in fixed position upon this post. A gear-wheel g is loosely journaled upon the post below the ratchet-wheel, the latter being preferably provided with a depending hub h, upon which by means of a suitable washer the gear is held. This gear-wheel is connected, by means of a spring-pawl j, with the teeth of the ratchet-wheel f, so that the gear may revolve in one direction and be 70 held against revolution in the opposite direction. Into the teeth of the gear g meshes the prime pinion c' of the train of clapper-operating pinions c c c, these pinions being mounted upon suitable pins connecting the 75 plates a a². The last pinion c² of the clapper-operating train has connected to it a star-wheel j', and the escapement j² of the clapper i engages with this star-wheel in a manner common in this class of bells.

Housed within the cup b and having one end rigidly secured to the fixed post d is a coiled spring l, the opposite end of which is connected to the plate a by means of a pin m, fixed to the plate. A thumb-piece a³ is 90 secured to the outside of the cup b for the purpose of turning it in the direction of the arrow, and a lug 5 projects from the bottom of the cup in such position as to strike against the extension 4 of the top plate 2 of the 95 clamp and limit the turning movement of the cup in the opposite direction.

The construction being as above described, the operation of the bell is as follows: The cup and the plates a and a², as also the clapper i and its train of operating-pinions c c c' c², being free to turn around the fixed post

are pressed constantly in one direction by the stress of the spring l , one end of which is secured to the post, as already described, and the other end of which is fixed to the plate a . The tension of this spring holds the cup and the parts carried thereby in such position that the lug 5 on its bottom is held in contact with the stop 4, projecting upwardly from the clamp. When it is desired to ring the bell, the cup b is turned in the direction of the arrow in Fig. 2 by pressure against the thumb-piece a^3 . This causes the cup and the train of clapper-operating pinions and the clapper itself all to turn around the post 15 in the same direction and tends also to turn the gear g in the same direction. Movement of this gear, however, in this direction is prevented by means of the spring-pawl j , and the gear being thus held against movement 20 the train of clapper-operating pinions travels around it and the clapper is operated by the consequent revolution of the pinions in a manner that is well understood. On releasing the thumb-piece a^3 the pressure of 25 the spring rotates the cup and its connected parts in the reverse direction and restores them to their original position, with the lug 5 against the stop 4. In this movement of the parts the frictional engagement between 30 the clapper-operating pinions and the gear g tends to carry the latter with them, and the inclination of the ratchet-teeth permits the spring-pawl to slip over them and allows the gear g to revolve backward with the train of 35 operating-pinions without causing any individual rotation of the latter. It will be understood from this that the clapper is operated and the bell rung only when the cup is moved by pressing against the thumb-piece 40 a^3 in the direction of the arrow and that the only function of the spring is to restore the parts to their original position ready for a new impulse. It follows from this that the bell begins to ring immediately that pressure 45 is applied to the thumb-piece and that the duration of the ring is variable and dependent upon the extent of turning movement. It is also to be noted that the intensity of the ring and the rapidity of the strokes is dependent upon the speed with which the cup 50 is turned. A further advantage of the construction lies in the fact that the spring has nothing to do with the operation of ringing the bell, but only returns the parts to their original position for a new impulse. Thus a 55 very light and cheap spring is sufficient to do the work, and even should the spring break the bell would not be inoperative, as obviously the parts could be returned to their initial position by hand.

It is of considerable importance to cycle-riders that the ringing of the bell should begin instantly on the application of pressure to turn it, and it is characteristic of my construction that the clapper is operated posi-

tively by thumb-pressure and not by the compression and release of springs; and a further advantage of the arrangement is that it permits a relatively-large multiplying gear, as g , and a train of clapper-operating pinions which will produce a loud and continuous ring for a very small amount of movement of the thumb-piece.

Having thus described my invention, what I claim, and desire to secure by Letters Pat- 75 ent, is—

1. In an alarm-bell for bicycles and the like, the combination of the crown, a fixed post, a ratchet-wheel secured to the post, a gear-wheel journaled on the post, a plate 80 carrying a clapper and pinions meshing with said gear, and a spring tending to revolve the plate, the gear and the pinions in one direction, the gear having a pawl engagement with the ratchet, whereby it will be held 85 stationary by the ratchet when the spring is wound up, but will revolve with the pinions around the ratchet when the spring is released.

2. In an alarm-bell for bicycles and the like, the combination of the crown, a fixed post, a ratchet-wheel fixed to the post, a gear-wheel journaled on the post, a cup under the crown, a clapper and operating-pinions carried by said cup, connections between said 95 ratchet and gear to hold the latter stationary and cause the pinions and clapper to operate when the cup is manually turned, and a spring for returning the parts to their normal position.

3. In an alarm-bell for bicycles and the like, the combination of the crown, a fixed post, a ratchet-wheel secured to said post, a gear-wheel journaled on the post, a cup under the bell having a thumb-piece connected 105 thereto, a clapper and train of operating-pinions carried by the cup and connected to the gear, a pawl connection between the ratchet and gear to hold the latter fixed when the cup is manually rotated, and a spring for 110 returning the parts to their normal position.

4. In an alarm-bell for bicycles and the like, the combination of the crown, a fixed post, a ratchet-wheel secured to the post, a gear-wheel journaled on the post and having 115 a spring-pawl connecting it with the ratchet-wheel, a cup under the bell having a thumb-piece for turning it in one direction around the post and a spring for returning it to position, a fixed stop against which the 120 spring holds the cup, a plate or frame secured to the cup and carrying a clapper and train of operating-gears in mesh with the first-mentioned gear.

In testimony whereof I affix my signature 125 in presence of two witnesses.

EZRA ARTHUR NEWHALL.
